BASE FOR RADIOTUBES

Filed Nov. 8, 1926

UNITED STATES PATENT OFFICE

CLAIR J. TERRILL, OF DAYTON, OHIO, ASSIGNEE TO THE KURZ-KASCH COMPANY, OF DAYTON, OHIO, A CORPORATION OF OHIO

BASE FOR RADIOTUBES

Application filed November 8, 1926. Serial No. 146,943.

My invention relates to thermionic valves or radio tubes and the like and more particularly to an improved base therefor adapted to minimize the transference of energy between the various circuit leads and contact prongs.

The standard and conventional radio tube construction at the present time includes either an evacuated or a gas filled vessel or bulb usually of glass, containing the various elements, i. e., the cathode or filament, the grid or modulating element, and the plate or anode element. It is customary to provide a cup shaped base of insulating material into which the vessel is seated and through which circuit leads extend from the elements to corresponding contact fingers or prongs projecting from the bottom of the base. Although such contact fingers or prongs are spaced apart and separated by intermediate areas of insulating material there occurs never-the-less an intertransfer of electrical energy, particularly at high radio frequencies, and current losses and leakage from one terminal prong to another either through the material of the base or over the surface thereof due to hygroscopic effects.

In the present invention there is contemplated the separation of the contact terminals or prongs by an intervening air gap, which affords a most efficient dielectric resistance.

To this end a radio tube base of insulating material and of substantially standard design is transversely slotted across its bottom, and intermediate the contact terminals or prongs, thereby forming isolated lugs or ears, each carrying a contact terminal or prong and separated from each other by an intervening air gap.

The object of the invention is to increase the efficiency of thermionic valves and the like by improving the dielectric resistance between the circuit leads and terminals minimizing current losses and transfer of energy and the elimination of objectionable feed back effects at this point.

With the above primary and other incidental objects in view as will more fully appear in the specification, the invention consists of the features of construction, the parts

and combinations thereof, and the mode of operation, or their equivalents, as herein-after described and set forth in the claims.

In the accompanying drawing, wherein is shown the preferred but obviously not necessarily the only form of embodiment of the invention, Fig. 1 is a perspective view of a thermionic valve or radio tube provided with a base embodying the present invention. Fig. 2 is a bottom plan view thereof. Fig. 3 is a vertical sectional view. Figs. 4 and 5 illustrate modifications of the construction. Fig. 6 is a bottom plan view of the tube base illustrating a modification wherein the base is recessed intermediate the contact prongs but not perforated. Fig. 7 is a perspective view illustrating a modification wherein the slotted openings in the bottom of the base are extended upwardly in the side wall thereof.

Like parts are indicated by similar characters of reference throughout the several views.

In the drawings there is shown a conventional type of radio tube wherein 1 indicates the bulb containing the several elements, and 2 the base of dielectric material in which the bulb 1 is secured and from which project the contact terminals or prongs 3. Two of the prongs or terminal contacts 3 pertain to the cathode or filament, while one of the remaining prongs 3 pertains to the grid element and the other to the plate or anode element.

Transverse slots 4 are formed in the bottom of the base 2 intermediate the prongs 3, thereby leaving separated lugs or ears 5 upon which the prongs 3 are supported. These lugs or ears 5 may be variously shaped and proportioned to increase the intervening air gap and so increase the dielectric resistance. The slots 4 or air gaps may be extended up the sides of the base 2 as shown at 6 to further isolate the lugs 5 and their supported prongs 3.

The air gap base forming the subject hereof, is in effect a sleeve like body 2 of insulating material having at one end thereof a series of radially disposed internal lugs 5 supporting the contacts 3. The main body or

sleeve 2 is merely a rim exteriorly connecting the lugs 5 and engaging the bulb 1.

While the separation of all the contact terminals is preferred, the losses are most likely to occur between the grid and plate or between grid and filament or plate and filament terminals and are negligible between the two filament terminals. Hence the filament terminals may be carried upon a common sector lug 7 as shown in Fig. 4 and the grid and plate terminals may be separated therefrom and from each other by intervening air gaps. Likewise if desired only one of the terminals may be isolated from the remaining contact prongs 3 by providing only an arcuate slot 8 separating the lug or ear carrying the single prong from the section of the bottom which is common to the remaining contact prongs.

The separation of the circuit lead contacts by an air gap is found to materially increase the efficiency of the tubes and eliminates much distortion, and current losses and interference due to radio frequency activity between the various circuits.

As a further modification there is shown in Fig. 6 air gaps 4' separating the prong supporting portions 5' and which do not extend entirely through the material but comprise depressions in one or both sides of the bottom section of the base. In lieu of an open slot extending through the bottom section such slots or air gaps 4' are extended only partially through the material forming grooves or abrupt recesses. Not only may the prong supporting areas 5' be separated from each other by the grooved air gaps 4', but they may be separated from the main sleeve or body 2 by a similar annular depression 9. Such annular air gap 4' may be advantageously combined with the open slot construction as shown in Fig. 2. Such grooved depressions interrupt the hygroscopic conductivity over the surface of the material and necessitate successive changes of direction of such current leakage which does not readily change its course. Thus the resistance is increased and such losses minimized while maintaining a closed base to exclude air and moisture from the element leads.

From the above description it will be apparent that there is thus provided a construction of the character described possessing the particular features of advantage before enumerated as desirable but which obviously is susceptible of modification, in its form, proportions, and arrangement of parts, without departing from the principle involved or sacrificing any of its advantages.

Having thus described my invention, I claim:

1. A thermionic valve including, a base secured thereto, a plurality of contact terminals on said base to be connected by circuit leads to the valve elements, said contact terminals being separated by horizontally and

vertically disposed intervening air gaps in the bottom and side walls of the base.

2. A thermionic valve including, a base therefore, and contact terminals carried by the base to be connected with the valve elements, said base having therein transverse slots intermediate the contact terminals separating by air gaps the portions of the base carrying the individual terminals said slots being extended vertically from the bottom upwardly within the side walls of the base.

3. A base for a radio tube comprising a cup-shaped body of dielectric material, and a series of spaced electrical terminals located in the bottom thereof, the bottom being recessed intermediate the terminals to increase the dielectric resistance, said recess being extended above the bottom of the body into the side walls of the cup shaped body.

In testimony whereof, I have hereunto set my hand this 19th day of October, A. D., 1926.

CLAIR J. TERRILL.
